UNITED STATES PATENT OFFICE.

GEORGE L. OSWALT, OF CLINTON, INDIANA.

MOLD FOR FORMING BRICKS OR CONCRETE BLOCKS.

Application filed April 4, 1922. Serial No. 549,568.

To all whom it may concern:

Be it known that I, GEORGE L. OSWALT, a citizen of the United States, residing at Clinton, in the county of Vermilion and State of Indiana, have invented certain new and useful Improvements in Molds for Forming Bricks or Concrete Blocks, of which the following is a specification.

This invention relates to molds for forming concrete blocks or bricks and has for its object the provision of an inexpensive construction, by the use of which a large number of blocks may be formed at a single operation and in which the parts will be so arranged that they may be readily disassembled to facilitate removal of the blocks or to be stored in a small compass. The objects of the invention are contained in such a device as is illustrated in the accompanying drawings, and the invention resides in certain novel features which will be particularly pointed out in the claims following a detailed description.

In the drawings—

Figure 1 is a side elevation of my improved mold arranged upon a truck for transportation;

Fig. 2 is a transverse section on the line 2—2 of Fig. 1;

Fig. 3 is a perspective view of one corner of the mold arranged for use;

Fig. 4 is an enlarged detail section showing the manner in which the forms are fitted together;

Fig. 5 is a detail perspective view showing the several parts of the mold separated but approximately in their proper relative positions;

Fig. 6 is a view similar to Fig. 5 but looking at the opposite of the form.

The mold is preferably arranged upon a truck 1 which may be of any convenient or preferred form and is employed so that the mold may be readily transferred from the pouring point to the drying point. Upon this truck, I secure the longitudinal supporting rails or sills 2 which are of a step formation in transverse section, thereby providing a ledge 3 and a vertical shoulder 4.

At intervals in the ledge 3, I form sockets 5 which are adapted to receive tongues 6 formed at the ends of the transverse partitions 7 which extend between and are supported by the sills and constitute the main

members of the forms. Between the ends of the several transverse partitions or form members 7 and the adjacent shoulder 4, I place a side plate 8 which extends the full length of the mold and closes the side thereof. At the ends of the sills, I arrange the end plates 9 which have their lower corners resting upon the ledges 3. The partitions 7 and one end plate 9 are each constructed with longitudinal offsets or ribs 10 intermediate their upper and lower edges on one face and, in assembling the parts, the said ribs or offsets are all faced in the same direction so that, when concrete is poured into the mold, the resulting blocks will each have a longitudinal groove in one side or face, and may be readily arranged so as to provide air spaces within the wall to prevent the accumulation of moisture. The grooves produced in the blocks will also facilitate handling of the same. For convenience, the face having the ribs will be termed the front face. The rear face of each partition is plane but projecting from said face of each partition and one end plate are division plates 11 which have straight upper and lower edges, but have the rear edge formed with a notch 12 to fit over the rib or offset 10 upon the abutting partition 7. The said division plates will, consequently, fit closely to the several partitions and will avoid the formation of open joints or seams through which the green concrete or other material might seep so that the block formed in each cell or space of the complete mold will be free of blemishes and will have the desired outline. Projecting from the front face of each partition, in the horizontal plane of the lower ends of the division plates are bottom plates 13 separated by spaces 14 which are just wide enough to snugly receive the lower ends of coacting division plates 11 so that when two partitions 7, with the parts carried thereby, are arranged in proper relation, a row of molds will be produced into which green concrete or other plastic material may be poured without loss by seepage.

The lower edges of the side plates 8 are held against outward movement under the pressure exerted thereon by the green concrete by reason of their engagement with the vertical shoulders 4 of the sills 2. To further withstand the outward pressure ex-

2
erected by the concrete, brackets 15 are secured to the side and the end plates at the corners of the mold, as shown most clearly in Fig. 3, the said brackets being conveniently angularly bent straps secured to the respective plates by bolts or screws. By referring to Fig. 1, it will be noted that the truck projects beyond the ends of the mold and braces 16 are arranged between the outer extremities of the truck and the upper brackets 15 so as to further reinforce the upper portion of the mold and enable it to withstand the pressure exerted therein. These braces may advantageously be equipped with turn buckles 17 whereby their effective length may be readily adjusted.

The several parts constructed as described are assembled upon the truck in the relative positions indicated in Figs. 4 and 5, and a large number of compartments will thus be produced within the outlines of the mold. Mixed concrete is poured into all the compartments and the truck is then shipped to the drying point where the concrete is permitted to set. The partitions and division plates may be varied in number so as to vary the dimensions of the finished blocks and the offsets in the partitions may be omitted, if preferred, so that smooth or plane-faced blocks may be produced. When the blocks have set and are thoroughly hardened, the several plates and partitions constituting the mold may be easily withdrawn from about and between the blocks so that the latter may be at once shipped to the point of use. A mold constructed according to my invention will be light, cheap and easily manipulated. The form consisting of the members 7, 11 and 13 is one complete structure and the various members or elements may be integrally united or rigidly secured together by brazing or other convenient means. A rib or shoulder 18 may be formed on the rear face of each partition 7 and one end plate 9 to provide a rest or support for the free ends of the abutting bottom plates 13.

It will, of course, be understood that the offsets or ribs 10 may be omitted and the transverse partitions 7 may have both faces plane, in which event the notches 12 will be also omitted and the edges of the division plates will be straight to form close contact with the abutting partition.

Having thus described the invention, what is claimed as new is:

1. A mold for forming blocks comprising a pair of parallel supporting sills, forms comprising partitions disposed transversely between said sills and supported by the same, spaced bottom plates projecting from the front faces of the partitions at the lower edges thereof, division plates projecting from the rear faces of the partitions with their lower ends fitting in the spaces between meeting bottom plates, and side plates and end plates supported by the sills and closing the sides and ends of the spaces defined by the partitions and the division plates.

2. A mold for forming blocks comprising a pair of parallel sills provided with longitudinal vertical shoulders between their side edges and having spaced recesses in their upper sides at said shoulders, transverse partitions resting upon and extending between said sills and provided at their ends with depending tongues to engage the recesses in the sills, bottom plates between the partitions, side plates resting on edge upon the sills against the shoulders thereon and against the ends of the transverse partitions, end plates supported at their ends upon the sills and extending between the sills, and fastening devices applied to the outer faces of the side plates and the end plates at the junctions of the same.

3. A form for molds comprising a partition plate, a series of parallel vertical division plates projecting from one face of the partition plate, and a series of spaced bottom plates projecting from the opposite face of the division plate, the spaces between the bottom plates being alined with the division plates.

4. A form for molds comprising a partition plate, a series of spaced bottom plates projecting from the front face of the partition plate, a series of vertical parallel division plates projecting from the rear face of the partition plate with their lower ends adapted to fit between the bottom plates projecting from an adjacent partition plate, and a rest on the rear face of the partition plate for the free ends of the last-mentioned bottom plates.

In testimony whereof I affix my signature.
GEORGE L. OSWALT. [L. S.]
